VEGETABLE PEELER

William E. Urschel, Valparaiso, Ind.

Application February 9, 1934, Serial No. 710,407

14 Claims. (Cl. 146—49)

This invention relates to vegetable peelers and particularly to that type of machine described in the application for Letters Patent entitled "Vegetable peeler", Serial Number 626,148, filed July 29, 1932, in the name of William E. Urschel.

The objects of the present invention include the provision of:

A new peeling machine of improved construction having but few parts, movable and stationary, thereby lending to its efficiency, decreasing wear and simplifying operation;

A simplified form of main frame easily assembled but amply rigid for the purpose;

An improved hopper having a hinged cover to confine spray or solid matter that may be cast from the moving peeling elements;

An improved discharge spout and leak-proof door therefor;

A novel combination of mechanical means for rotating and oscillating the peeling members of the device;

A new and improved mounting facilitating ready removal of the peeling rollers from the device for cleaning or the like;

Means for temporarily holding the peeling members apart to adapt the machine and the members themselves to cleansing without the rollers first being taken from the machine; and

A suitable flexible motor support constantly applying a predetermined tension to the drive belt connected thereto.

These objects, and such other objects as may hereinafter appear, are obtained by the novel construction, unique arrangement and improved combination of the elements of the device illustrated in the accompanying four sheets of drawings hereby made a part of this specification, and in which:

Figure 1 is a front elevation of a device embodying the preferred form of the present invention;

Figure 2 is a right end elevation of the device, with respect to Figure 1, the drive belt and pulley being removed for better illustration;

Figure 3 is a left end elevation of the device with respect to Figure 1;

Figure 4 is a fragmentary view of the device taken from the front with portions of the hopper and housing broken away to display the driving mechanism and peeling rollers;

Figure 5 is a sectional view of the machine taken on line 5—5 of Figure 1 looking in the direction indicated by the arrows;

Figure 6 is a sectional view of the machine taken on the line 6—6 of Figure 1 looking in the direction indicated by the arrows;

Figure 7 is an enlarged sectional view of a peeling member taken longitudinally thereof;

Figure 8 is an end view of the internal gear illustrated in Figure 9 and showing its connection with gears for driving the peeling rollers; 5

Figure 9 is an enlarged sectional view of an internal gear forming a part of the driving mechanism at the right end of the device and of the mounting therefor;

Figure 10 is a transverse fragmentary sectional view of the device, taken at the line 10—10 of Figure 4 looking in the direction of the arrows; 10

Figure 11 is an enlarged side view of the main drive shaft illustrating the bearings therefor in detail; and 15

Figure 12 is an enlarged fragmentary sectional view showing parts of the driving mechanism of the device, the view being taken on the line 12—12 of Figure 10 in the direction of the arrows.

Like reference characters are used in the drawings and throughout the following description for designating similar parts of the device. 20

Support for the whole apparatus is upon a frame indicated generally by the reference character 20 and illustrated in Figures 1, 2, and 3. 25 Legs 21, at the right end of the frame, Figure 1, are attached to and held in spaced lateral relation by an end plate 22 of a housing designated 23. A strap 24 holds the lower part of legs 21 in predetermined spaced relation. 30

The left end of the frame 20 includes legs 25 held in spaced relation at their lower ends by a strap 26. The two pairs of legs 21 and 25 are additionally braced at their lower ends by rods 27 which are encased in tubular spacing members 28. 35 Nuts 29 threaded upon the ends of the rods 27 draw the legs together against the ends of the spacing members 28. At the left end of the housing 23 is a casting 30 for forming a part of such end and anchoring the upper ends of the legs 25. 40

Peeling of vegetables is accomplished by the rotating and oscillating of abrasive cylinders 31 illustrated in Figures 4, 5, 6, and 7. If desired, the peripheral portions 31a of the cylinders 31 may comprise porcelain in which a fine abrasive 45 32 is baked or attached thereto in any other conventional method.

Such cylinders 31 may be a single or continuous tube of porcelain or they may be made up of several tubular sections 31a held securely on cylinders 33 by collars 34 and 35 threaded upon said cylinders. 50

Washers 36 of resilient material may be disposed between the porcelain members 31a and collars 34 and 35 to distribute pressure evenly over 55

the ends of such members and for their protection. At one end of each of the cylinders 31 are roller bearings 37 held in position on a shaft 38 by a shoulder 39 of a gear 40 and washer 41.

5 Washer 41 is secured by spur gear 40, whose hub is in threaded relation with the collar 35, against an end of its respective sleeve or tube 33. Grooves 42 may be provided in gear 40 to prevent the escape of lubricant from the bearings 37 and 10 also to protect said bearings from dirt and the like. Roller bearings 37a at the right end of cylinder 31 are held in position on the shaft 38 by means of collars 43 and 44 pressed into or otherwise secured in the tube 33. Grooves 45 in the 15 collar 44 serve the same purpose as the grooves 42 in gear 40.

Sections 46 at the ends of each of the shafts 38 are square and are adapted to fit into the complementary square apertures 47 of the roller holders 48, Figures 4 and 8, where they are secured by the washers 49 and nuts 50, see Figure 7. The holders 48 at the drive or gear end of the shaft 38 are each supported upon a shaft 51 for oscillative movement therewith, see Figures 8 and 9. A key 25 52 passes through each shaft 51 and into a slot 53 in the holder 48 attached thereto and, therefore, the fit between the ends of the shafts and the central apertures 53a of the holders 48 need not be tight so that disassembly of the parts is made 30 easy. Washer 54 acts as a spacer member between key 52 and sleeve 55. The holder 48 at the opposite end of each pair of cylinders is pivotally mounted at its center to permit of oscillative movement of the rollers.

35 Spur gears 40 of each pair of cylinders 31 are driven by a bell-shaped internal gear 56 the hub of which is in threaded connection with the extended hub 57 of a gear 58. Roller bearings 59 in opposite ends of the hub 57 of gear 58 are held in 40 position on the sleeve 55 by means of a flange 61 of the hub 57 and a face 62 at the hub of the internal gear 56. Tubular spacer members 63 holds the said bearings in spaced relation. Grooves 64 and 65 within the flanges 61 of gears 45 58 and within the hubs of gears 56, respectively, protect bearings 59 from dirt and the like and prevent the escape of lubricant from said bearings. Sleeve 55 is inserted in a circular aperture 66 in plate 22 and there held in position by nuts 67 50 in threaded relation with the said sleeve. The present embodiment of the invention has two pairs of cylinders 31. In Figure 4, there is shown an internal gear 56 for driving each of said pairs of cylinders. A mounting similar to that just described is had for each of the gears 56.

60 Gear 68 (Figures 4, 10, and 11), which drives each of the gears 58, is keyed to a shaft 69 at the other end of which is pinned or otherwise secured a drive pulley 70. The shaft 69 is mounted upon 65 the roller bearings 71 which, in turn, are held within a bearing housing consisting of complementary parts 72 held to the plate 22 by bolts 73 (Figure 2). The bearings 71 are held in spaced relation by a tube 74. Grooves 75 at the ends of 70 housing members 72 protect roller bearings 71 from abrasive or corrosive foreign matter and prevent the escape of lubricant from about the bearings.

75 Spur gear 76 is keyed to the left end of shaft 69 for driving gear 77 keyed and pinned to shaft 78 by key 79 and pin 80. Shaft 78 is mounted upon the roller bearings 81 which are supported within the housing 82. Shoulder 83 of the housing 82, the annular lubricant sealing member 84,

and the tube 85 coact to hold bearings 81 in a fixed position on shaft 78.

5 Grooves 86 and 87 within the annular sealing member 84 and the bearing housing 82, respectively, have been provided to retain lubricant about the bearings 81. Bearing housing 82 and lubricant seal 84 are secured to the plate 22 by bolts 88 (Figure 2). The right end of shaft 78 (Figures 4 and 12) has been offset to provide a crank section 89. A stud 90 is in threaded relation with the crank section 89 and selectively positioned relatively thereto by the abutment of the shoulder 91 thereof with the bottom of a recess 92 within the crank section.

Depending pivotally from the stud 90 is a connecting member 93 connected to a link 94 by a pin 95 and by means of a key 96 whose end is thrust into a notch 97 of the link 94 by the force of a spring 98. The shank of key 96 is reciprocably contained in apertured ears 99 projecting from the same side of an arm 100 extending from the pendulous connecting member 93. Spring 98 impingingly presses between the ear 99 near the outer end of the arm 100 and a pin 101 passing through the shank of the key 96. By manipulating the key 96 and the members 93 and 94 the end of such key may be removed from notch 97 and placed in notch 102 of the link 94. An arm 103 secured to the lower of the two shafts 51 is pivotally connected to link 94 by pin 104. The depending member 93 is pivotally connected to a second arm 103 upon the upper and rearmost of the two shafts 51 by a connecting rod or link 105. Revolution of shaft 78 actuates the linkages 93, 94, 103 and the two arms 103, to cause oscillative movement of shafts 51, which by means of the keys 52 therein cause the cylinder housings 48 and the cylinders 31 connected thereto to oscillate between the position shown in full lines in Figure 6 and the position shown by the dotted lines in that figure. To facilitate cleaning of the machine beneath the cylinders, the key 96 may be withdrawn from notch 97 of the member 94 and inserted in notch 102 thereof. This manipulation of the key 96 and members 94 and 105 causes pivotal movement of the arms 103 and shafts 51 to place the cylinders 31 in the position shown in Figure 5 to provide a much greater space between the two sets of cylinders than when they are in the working position illustrated in Figure 6. By spreading the two sets of cylinders, the device is easily cleaned.

55 A base plate 106 for the mounting of an electric motor 107 is hinged as indicated at 108 to the top of the back side of the housing 23 (Figure 2). The motor 107 attached to hinged mounting 106 by bolts 109 drives the main shaft 69 by means of a pulley 110, a belt 111, and the pulley 70. A spring 112 placed about a rod 113 (Figures 1 and 2) exerts a pressure against washer 114 and nut 60 115 to urge the motor mounting upwardly thereby providing automatic tension adjustment for the drive belt 111. Rod 113 is reciprocably mounted at its lower end in angle clip 116 secured to the front leg 21 by bolts 117, and has its uppermost portion inserted in a circular aperture 65 in the motor mounting at point 118.

Hereinafter it has been explained that the cylinders 31 are arranged in pairs, each pair constituting a unit. The unit at the front of the 70 device is the lower of the two. From Figure 4 it will be seen that the left end of the peeling cylinder units and comprising roller holders 48 are adapted to rock or oscillate about respective studs 119 anchored in castings 120. That is, the 75

studs 119 provide mountings for the castings 48 at the left end of the cylinder units much as do the shafts 51 at their right end and with the exception that the keys 52 prevent rotative movement of the castings 48 relative to the shafts 51.

To take the peeling cylinder units out of the machine for any purpose such as cleaning, repair or replacement, the two capscrews 121 (Figure 3) securing each of the castings 120 to the 10 end of the housing 23 are loosened to permit removal of the castings. The peeling cylinder units then may be withdrawn through circular openings 121a (Figure 4).

A portion of the housing 23 consists of a hopper 122 having front and back sides 123 and 124 in common with the front and back sides of the housing, an end wall 125 in common with the left end of the housing (Figure 4), and an end wall 126 depending downwardly into the housing. In 20 Figure 6 it is shown that the lower edge of the end wall member 125 contains juxtaposed arcuate indented sections 127 cut upon a radius corresponding substantially to that of circular plates 128, which are attached to the roller holders 48 by means of lugs 129 to aline with and assist the wall member 125 to complete the end wall of the hopper and housing. Similarly, at the opposite end of the hopper (Figure 5), the wall member 126 contains indented arcuate sections 30 130 which are filled by circular plates 128 supported upon lugs 129 of the roller holders 48 of the units. Plates 128 permit of the units oscillating while at the same time retaining the vegetables within the hopper.

35 A spray pipe 131 is suitably suspended within the hopper 122 at a position such as is shown in Figure 6. The purpose of said pipe 131 is to spray a liquid over the vegetables to clean them while they are being peeled and to wash the refuse 40 toward and out of the refuse spout 132.

A hinged cover 133 is provided to confine the spray and particles of vegetable peelings or skins within the hopper during the peeling operation. Rivets 134 serve to pintle ears 135 at the back 45 corners of the cover to the hopper end members 125 and 126 (Figure 6).

The peeled vegetables are discharged through opening 136 at the front side of the hopper 122 and guided therefrom into any suitable receptacle by the spout 137 riveted to the hopper wall about the opening. A hinged door 138 with its lower edge adapted for fitting into groove 139 (Figures 5 and 6) may be employed for closing the opening 136 during the peeling operation. 55 Slots 140 in ear-like extensions 141 of the door 138 and through which a rod 142 passes coact with such rod to form a hinged mounting for the door. Rod 142 is suitably secured to the upper end of side members of spout 137. A handle 60 143 riveted to door 138 provides for easier manipulation thereof.

The bottom of the housing 23 forms a drain indicated generally by the reference character 144. Substantially all of the refuse consisting 65 of waste water and particles of peeling is conducted away through the drain.

The motor 107, by means of the belt 111 and pulleys 110 and 76, causes rotation of main drive shaft 69. The two spur gears 68 and 76 secured 70 near the left end of said shaft 69 (Figure 4) drive the gears 58 and 77, respectively. Gear 68 drives the mechanism for rotating the cylinders 31 about their individual axes while gear 77 drives the mechanism for oscillating the paired rollers. 75 Gears 58 revolve about and independently of

shafts 51 to rotate the bell-shaped internal gears 56. From Figure 8, it is apparent that rotation of the internal gear 56 will cause rotation of the two spur gears 40 attached to the cylinders 31 thereby rotating said cylinders.

Gear 77 drives shaft 78 to impart a circular movement to the member 93 and hence oscillatory movement to the arms 103 by means of the connecting members 94 and 105. Arms 103 impart a like oscillatory movement to the two units 10 or pairs of cylinders 31 to which they are respectively connected by shafts 51 and the castings 48. This oscillative movement of the paired cylinders takes place during the time of their rotation to change the contour of the supporting 15 surface of the bed of cylinders so that all sides of vegetables or other articles supported thereon for peeling may have their peel come in contact therewith. All of the cylinders rotate in the same direction.

This rotative movement of the cylinders together with their oscillating or rocking motion causes the whole mass of vegetables in the hopper 122 to slowly revolve in a unitary mass thus allowing each individual vegetable to come in 20 contact with each cylinder 31. After each individual vegetable comes in contact with the last of the cylinders 31 traversed thereby, it is carried upwardly and toward the back of the mass to again be conducted over the cylinders and the 25 process repeated until all of the articles are peeled. The rocking movement of the cylinders 31 facilitates more rapid peeling and causes those vegetables to be more thoroughly agitated. The constant turbulation of the articles by the up 30 and down movement of the cylinders overcomes any tendency of the vegetables to pack into a relatively stationary group.

Upon completion of the peeling process, the vegetables in hopper 122 are released by opening 40 the door 138 and are guided by the chute 137 into a suitable receptacle.

What is claimed as new and is desired to be secured by Letters Patent of the United States is:

1. A peeling mechanism comprising a bed of 45 roughened cylinders for supporting articles to be peeled, means for moving each adjacent cylinder bodily up and down to change the level of sections of the articles supporting area of said bed, and means for rotating said cylinders during such movement.

2. A peeling mechanism comprising a bed of juxtaposed roughened members rotatable upon parallel axes and providing support for articles to be peeled, means for moving each adjacent 55 member bodily in an opposite up and down direction transversely of such axes to change the levels of sections of the supporting area of said bed, and means for rotating said members during such movement.

3. A peeling mechanism comprising a bed of a plurality of pairs of roughened members rotatable about parallel axes and providing support for articles to be peeled, independent supporting means for each pair of members, the 65 pairs of members being in staggered arrangement as to height, means adapted to produce oscillative movement of each independent supporting means within said bed, whereby to oscillate said pairs of members, and means concurrently rotating the individual members.

4. In a peeling mechanism, a combination of a hopper, a plurality of pairs of rotatable peeling rollers, an internal planetary gear for each pair of rollers, means for rotating said internal 75

- gear, a gear connected to each roller and enmeshing with the teeth of said internal gear whereby to drive said gears, and means for automatically shifting each of said gears bodily in an arcuate path concentric with the path of rotation of said internal gear.
5. In a peeling mechanism, a combination of a hopper, a plurality of pairs of rotatable peeling rollers, an internal planetary gear for each pair of rollers, means for rotating said internal gear, a gear connected to each roller and enmeshing with the teeth of said internal gear whereby to drive said gears, and means for automatically shifting each of said gears bodily in an arcuate path concentric with the path of rotation of said internal gear, and manual means for additionally shifting each of said gears in an arcuate path.
6. A peeling mechanism comprising a bed of adjacent, paired, roughened cylinders rotatable about parallel axes for supporting articles to be peeled, means for simultaneously oscillating the cylinders of each pair about a longitudinal axis approximately midway between the cylinders of each pair to change the level of all of the cylinders in said bed, and means for rotating said cylinders individually during such oscillation.
7. A peeling mechanism comprising a bed of adjacent, paired, roughened cylinders rotatable about parallel axes for supporting articles to be peeled, means for simultaneously oscillating the cylinders of each pair about a longitudinal axis approximately midway between the cylinders of each pair to change the level of all the cylinders in said bed, and means for rotating said cylinders in the same direction during such oscillation.
8. A peeling mechanism comprising a bed of paired, roughened cylinders rotatable about parallel axes, means for separately and simultaneously moving the cylinders of each pair in opposite directions about an axis parallel to the cylinders to shift the position of each of the cylinders simultaneously to change the level of the cylinders in the surface of said bed, and means for continuously rotating said cylinders.
- 40 9. A peeling mechanism comprising a hopper, a bed of paired, adjacent, roughened cylinders rotatable about parallel axes and forming the bottom of the hopper, means for separately and simultaneously moving the cylinders of each pair in opposite directions about an axis parallel to the cylinders to shift the position of each of the cylinders simultaneously to change the level of the cylinders in the surface of said bed, and means for continuously rotating said cylinders.
- 45 10. A peeling mechanism comprising a bed of paired, roughened cylinders rotatable about parallel axes, means for separately and simultaneously moving the cylinders of each pair in a predetermined path in opposite directions about an axis parallel to the cylinders to shift the position of each of the cylinders simultaneously to change the level of the cylinders in the surface of said bed, and means for continuously rotating said cylinders.
- 50 11. A peeling mechanism comprising a bed including a plurality of roughened cylinders rotatable about parallel horizontal axes, means for simultaneously moving all adjacent cylinders bodily in opposite directions, up and down, to change the level of sections of the article supporting area of said bed, and means for continuously rotating said cylinders during such motion.
12. A peeling mechanism comprising a hopper, a bed including a plurality of roughened cylinders forming the bottom of said hopper and rotatable about parallel horizontal axes, means for simultaneously moving all adjacent cylinders bodily in opposite directions, up and down, to change the level of sections of the article supporting area of said bed, and means for continuously rotating said cylinders during such motion.
13. A peeling mechanism comprising a bed of roughened cylinders rotatable about parallel horizontal axes, means for simultaneously moving all adjacent cylinders bodily in opposite directions, up and down, to change the level of sections of the article supporting area of said bed, and means for continuously rotating said cylinders in the same direction during such motion.
- 40 14. A peeling mechanism comprising a bed, including a plurality of peeling members rotatable about parallel horizontal axes, means for simultaneously moving all adjacent peeling members bodily in opposite directions, up and down, to change the level of sections of the article supporting area of said bed, and means for continuously rotating said cylinders during such motion.

WILLIAM E. URSCHEL. 50
